GARMENT HANGER

John G. Warmath III, Brooklyn, N.Y., assignor to Yankee Plastics, Inc., New York, N.Y., a corporation of New York

Filed Mar. 15, 1962, Ser. No. 69,286

Term of patent 3½ years

(Cl. D80—8)

FIG. 1

FIG. 2

FIG. 4

FIG. 1 is a front elevational view of a garment hanger showing my new design, the rear being substantially plain,

FIG. 2 is a side elevational view,

FIG. 3 is a top plan view thereof, and

FIG. 4 is an enlarged cross-sectional view thereof taken on line 4—4 of FIG. 1.

I claim:

The ornamental design for a garment hanger, substantially as shown and described.
